UNITED STATES PATENT OFFICE.

CLARENCE F. BLUE, OF WILKES-BARRE, PENNSYLVANIA.

SKIRT-HANGER.

No. 834,706.

Specification of Letters Patent.

Patented Oct. 30, 1906.

Application filed April 8, 1905. Renewed September 29, 1906. Serial No. 336,805.

To all whom it may concern:

Be it known that I, CLARENCE F. BLUE, a citizen of the United States, residing at Wilkes-Barre, in the county of Luzerne and State of Pennsylvania, have invented certain new and useful Improvements in Skirt-Hangers, of which the following is a specification.

The purpose of my invention is to provide an attachment for supporting a skirt which may be readily applied to certain well-known forms of coat or cloak hangers. The attachment may be made and sold with the hanger or made separately and attached to hangers already in use.

In the accompanying drawings, which illustrate my invention, Figure 1 is a perspective view of a coat-hanger having my improvements applied thereto, and Fig. 2 is a similar view of the parts composing one of the skirt-supporting devices detached from the hanger.

Referring to the drawings, A indicates a coat-hanger having a central supporting-hook 1, from which the body 2 of the hanger extends laterally in opposite directions, terminating in two elongated loops *a a*, which are intended to fit within and support a coat or cloak at its shoulders. As the coat or cloak hanger proper forms no part of my invention, a further detailed description is unnecessary. My invention is applicable to any of the usual forms of wire hangers having the loops *a a* at its ends.

In order to make the coat-hanger suitable for supporting a skirt also, I provide a pair of wire rods 3 and 4 for each loop of the hanger and a supporting device 5 for each pair of rods adapted to slide thereon. As shown in Fig. 2, the rods of each pair are made with similar downwardly-turned or hooked ends 3^a and 4^a, adapted to be fastened to the outer end portion of a loop on the hook, and the opposite ends of the rods are bent downwardly to form hooks 3^b and 4^b. These hooked portions 3^b and 4^b are bent laterally in opposite directions in order that they may be conveniently fitted around the side bars of a loop near its inner end.

In applying the attachment to the hanger 50 the hooks 3^a and 4^a are placed over the outer

end portion of the loop and then compressed around the wire of the loop, and the laterally-projecting hooks 3^b and 4^b are placed around the side portions of the loop near its inner end and compressed, as shown in Fig. 1, so as to firmly grip the side portions. The bars 3 and 4 are of similar length and when in position are approximately parallel, and the clip or supporting device 5, which engages the garment, may be moved from end to end of the bars, which both support and guide it. By adjusting the clips or supporting device 5 longitudinally the attachment may be made to support properly skirts of various widths. The supporting device or clip 5 may be of any design suitable for engaging the skirt. The device shown, consisting of a wire bent into a V shape, the apex of the device being bent slightly to one side, and having the coiled ends 6, which fit loosely around the guide-bars, is well adapted for the purpose.

Having described my invention, what I desire to secure by Letters Patent of the United States is—

1. A skirt-supporting attachment for coat or cloak hangers of the class having loops at their ends, said attachment consisting of a pair of wire rods and a garment-holding device movable upon said rods, each of said rods having a hook at one end adapted for attachment to the outer end of a loop on the hanger, and a hook at its opposite end adapted for attachment to a side portion of the loop.

2. The combination with a coat or cloak hanger having loops at its ends adapted to fit into the shoulders of a coat or cloak, of a skirt-hanger attachment arranged between the sides of each loop, each attachment consisting of a pair of bars connected to the sides and outer end of the loop, and a supporting device adjustable longitudinally on said bars and adapted to engage and hold a garment.

In testimony whereof I affix my signature in presence of two witnesses.

CLARENCE F. BLUE.
